UNITED STATES PATENT OFFICE.

GEORGE JACOBS, OF CLEVELAND, OHIO.

CREDIT-ACCOUNTING APPLIANCE.

1,130,823.

Specification of Letters Patent.

Patented Mar. 9, 1915.

Application filed June 14, 1912. Serial No. 703,714.

To all whom it may concern:

Be it known that I, GEORGE JACOBS, a citizen of the United States, residing at Cleveland, in the county of Cuyahoga and State of Ohio, have invented a certain new and useful Improvement in Credit-Accounting Appliances, of which the following is a full, clear, and exact description, reference being had to the accompanying drawings.

10 This invention relates to filing devices of the type known to the trade as "account registers," wherein the accounts in the form of slips are secured to the faces of a series of leaves or boards and in which said leaves 15 or boards are stacked or stored away so as to be readily accessible when desired, readily removable to a place of safe-keeping upon occasion, and easily returned to storage position when not in immediate use.

20 In devices of this kind, each leaf or board is provided with a suitable number of slip-holding devices or clips, each holding device or clip being numbered and the register being provided with an index whereon the 25 names of the debtors or other parties represented by the numbers on the leaves and clips will appear.

A great many expedients for the stacking or other storing of the leaves or boards have 30 been proposed, but many of the expedients heretofore adopted have been deficient in certain particulars such as in necessitating the manipulation of the leaves or boards separately, the independent removal and re- 35 placement of the leaves or boards when it is desired to store them for safekeeping, and the necessity of working in different planes when consulting the account slip thereon. In the case of a register containing only a 40 small number of leaves or boards, the above noted objections are not of great importance because of the fact that the separate handling of two or three boards is not objectionable, and with a small number of boards 45 the working plane will not vary sufficiently to cause any particular discomfort or eye-strain. In the case of an account register comprising a large number of boards, these 50 considerations become of great importance.

55 It is the general object of this invention, therefore, to provide an account register of this type wherein the planes occupied by all of the leaves will be substantially fixed or permanent during the reading, filing, or inspecting operations, enabling the slips or

accounts to be inspected at a place convenient of access and capable of efficient illumination.

Another object of the invention is to provide a device of this kind having means for 60 securing account slips to both the front and back sides of the boards or leaves and in which the opposite sides of these leaves shall be held in substantially the same plane so as to facilitate access thereto. 65

A further object of the invention is to provide a device of this kind with an index so constructed, located, and supported as to be convenient of reference and renewal.

Another object of the invention is to provide a construction of great simplicity, reliability and cheapness whereby the foregoing results may be accomplished, while further objects and advantages of the invention will be made clear in the course of the 75 following description and claims.

Generally speaking, this invention comprises a modification of the invention described and claimed in my copending application, filed June 7, 1912, Ser. No. 80 702,321 and will be found to contain many points in common therewith.

In the drawings accompanying and forming part of this application I have illustrated one embodiment of this invention, although it will be understood that these drawings are intended to be explanatory merely of one form of my device, and that I do not restrict myself to the particular features of construction, proportion, or arrangement shown therein. 85 90

In these drawings, Figure 1 represents a front elevation of the essential parts of my improved account register, showing the leaves or boards in one position; Fig. 2 represents a similar view of the device showing another position which the leaves or boards may assume and illustrating the manner of maintaining the reading plane at substantially a fixed point; Fig. 3 is an elevation of the right hand end of the device showing the leaves in the position illustrated in Fig. 1; Fig. 4 is a central vertical cross sectional view taken transversely across the supporting means at one side of 105 the register, showing the lazy tongs, springs, and bottom plate; Fig. 5 is a perspective view of one of the corner pieces whereby the lazy tongs are secured to the bottom plate; Fig. 6 is a detail cross sectional view 110

taken upon the line 6—6 of Fig. 4 showing the method of securing one arm of the lazy tongs to one of said corner pieces; Fig. 7 is a plan view of the index leaf, a portion 5 of the transparent cover plate being broken away; Fig. 8 is a plan view of one of the account leaves showing the retaining clips; Fig. 9 is a transverse, cross-sectional view taken through the index plate showing an 10 index card on one side of the same and account clips on the other side thereof; and Figs. 10, 11, 12 and 13 are detail cross-sectional views corresponding to the similarly numbered lines of Fig. 7 and illustrating the preferred method of constructing the index leaf and securing the index 15 plate thereto.

Describing the parts by reference characters, 1 denotes a base plate or support 20 and 2 denotes generally the account leaves of the register, said base member being provided at separated points with yielding supporting devices, and said leaves being hinged together at their bottoms in such 25 manner as to permit them to be folded over onto one or the other of said supporting devices, and said supporting devices being so constructed as to maintain the upper surfaces of the uppermost leaf thereon substantially horizontal and substantially at a fixed 30 distance above the base member. Although it will be apparent that various expedients may be employed for effecting this general result, the preferred expedient consists in forming each of these supporting devices with lazy tongs in the manner now to be described.

At quadrangular points of the base member 1 are secured brackets 3 to the upper end 40 of each of which are pivoted the lowermost levers 4—4 of a pair of lazy-tongs. To the outer ends of the levers 4—4 other levers 5—5 are pivoted, the levers 5—5 being of substantially twice the length of the 45 levers 4—4 and parallel thereto. To the free ends of the levers 5—5 are pivoted other levers 6—6 whose length is substantially the same as that of the levers 5—5, and as many sets of such levers may be 50 employed as is required to afford the desired amount of movement. In this embodiment the levers 6—6 are the last of the series. At their points of intersection the levers 5—5 and 6—6 are pivoted upon the 55 reduced ends 7—7 of horizontal rods 8—8, said rods extending from the intersection of one set of lazy tongs to the like points of the similar set at the opposite side of the base member, as shown in Fig. 3. The middle 60 portions of these rods are preferably square in cross section, as illustrated in Figs. 3 and 4, for the reception of leaf-springs 9—9 which tend to maintain the lazy-tongs in extended position. The midpoints of 65 these springs may be secured to certain of

the rods as shown in Figs. 3 and 4 and their end portions may rest against the sides of other rods, the attachment of the springs to the rods preferably being effected by means of blocks 10—10 in order to prevent the 70 weakening thereof.

To the upper levers of each pair of lazy-tongs is secured a supporting plate 12 preferably of metal and having a peripheral up-turned flange 13. The attachment of the 75 lazy-tongs to these plates is conveniently effected by means of corner pieces 14 riveted or otherwise secured thereto and provided with slotted ears 15 receiving studs 16 carried by the free ends of the levers 6. This 80 construction secures each of the plates at substantially right angles to its respective lazy-tongs while the pivoting of the lower ends of the lazy-tongs to the bracket 3 permits the free rocking of the supporting device as may be necessary in the movement of 85 the leaves. In the embodiment shown herein I have illustrated a channel member 17 secured to the bottom of each of the plates 12 and receiving the midportion of a leaf 90 spring 18, the free ends of which bear upon one of the bars 8. However this arrangement is not mandatory, as in some instances the spring 18 would be secured to the bar 8, depending upon the number of such bars in 95 the lazy-tongs. The plate 12 is preferably cut away or notched on one or more points as indicated at 19 to permit the leaves thereon to be grasped more easily.

While it will be apparent that any desired 100 type of leaf may be employed and that many of the advantages of my improved construction yet secured, I prefer to employ leaves constructed and formed substantially as illustrated and described in my copending 105 application above referred to, each of said leaves comprising a flat metallic plate or web 25 provided at its edges with a suitable number of oppositely projecting discontinuous flanges 26—26. These flanges are then 110 embraced by a rim 27 whose lateral edges are folded inwardly as at 28 so as to embrace the inner faces of these flanges and maintain the rim in position on the leaf. These rims thus coöperate with the body of the plate 25 to form dish-shaped recesses capable of 115 holding a large number of account slips, and of engaging the rims of adjacent leaves so as to prevent mutilation of the slips or the admission of dust thereto. The outer 120 face of this rim may be provided at suitable points with slots 30 for the reception of the bodies 31 of index tabs 32 or handles 33, the flanges 34 whereof are embraced by the rim in the manner described in the 125 former application. The inner edges of the leaves may also be provided with hinge knuckles 35 for the reception of suitable pins 36 whereby the leaves are joined together.

The size of the leaves is such as to cause 130

them to be received snugly between the flanges 13 of the bottom plates no other securing means being necessary.

The middle plate of the series is preferably formed as an index plate and to this end it is provided with means for the reception of an index card and with a plate of transparent material by which this card can be covered. For supporting this card I preferably form the plate 25 with spaced outwardly bent integral ears 38 struck up from the body of the metal, certain of these ears having their ends bent inwardly parallel to the plate as shown in Fig. 11 and, other ears being bent outwardly at right angles to the plate as shown in Fig. 10. The index sheet preferably consists of a metal plate 39 having its edge portion resting upon the inturned ears and received between the outward ears, being thereby held a short distance away from the face of the leaf and prevented from shifting thereover. The index cards are then pasted to the sides of the plate 39 as shown at 40, sufficient space being left between the plates 25 and 39 to permit a considerable number of index cards to be superposed upon the plate without crowding or bulging. A frame 41, preferably of right-angle metal as shown, may be hinged to one side of the leaf as at 42 and provided with a transparent sheet 43 of glass or celluloid. The edge flanges of the angle members preferably fall immediately within the rim 27 as shown in Figs. 10 and 11 and the transparent plate may be secured in place by a metal strip 44 riveted in place. In the present embodiment, the heads of these rivets are arranged to engage the edges of the plate 39 to clamp the same against the inturned ears 38, and the frame 41 may be secured in closed position by suitable means such as the spring latch 45. The account-receiving leaves are provided with spring clips 48 of the usual or any desired type. In the present embodiment the rearward side of the index leaf is illustrated as provided with such clips, although it is obvious that both sides of this leaf may be used for index purposes if desired, or that a number of the separate leaves might be employed either partially or wholly for index purposes, as required by the size of the register or the fancy of the owner.

The register, as a whole, will be operated much like a large book, the leaves being turned from side to side as occasion may demand. The leaves being connected together at their inner edges, the upper surfaces thereof will be maintained in substantially the same plane irrespective of the number of leaves upon one or the other side of the device, while the upper surfaces of these leaves will be always at substantially the same angle to the horizontal because of the mode of connecting the lazy-tongs to the bottom

plates. This plane may be made nearly horizontal if desired, although in practice, it is probably better to incline them slightly toward each other as shown in Figs. 1 and 2. In case a plurality of leaves be turned over at one time the two supports will rock sidewise around the brackets 3 without cramping or binding, while if it be desired to remove these leaves for storage or safe-keeping it is merely necessary to transfer them all to one of the supporting members and then remove them bodily therefrom, the notch 19 permitting ready grasping thereof.

The size of the device is entirely a matter of convenience. The base member 1 may, if desired, rest upon the floor and carry lazy-tongs of a length sufficient to bring the leaves to such a height as to be readily referred to by an operator in standing position. Likewise it may be placed upon a desk or table and provided with a lazy-tongs of a correspondingly less height. Likewise the device may, if desired, be more or less completely inclosed in a casing of more or less artistic form without departing from the scope of my invention or sacrificing any of the advantages thereof. Furthermore, as will be obvious, it is not necessary to employ rigid leaves, but flexible leaves, such as those of a book are conceived to fall within the terms of certain of the claims appended hereto, whereby the use of my peculiar supporting devices as a rest for holding an atlas, encyclopedia, dictionary, or other large book is conceived to fall within the scope of my invention.

While I have necessarily described my invention in detail, I do not therefore propose to be limited to such details, except as the same may be positively included in the claims hereto annexed or may be rendered necessary by the prior state of the art.

Having thus described my invention, what I claim is:—

1. In a device of the character described, the combination, with a plurality of leaves hinged together at their inner edges, of a rigid supporting plate at each side of the point of hinging of said leaves and receiving the end leaves of the series respectively, means yieldingly maintaining said plates in elevated position, and means for permitting a limited movement of said plates toward and from each other while maintaining said plates substantially horizontal at all times.

2. In a device of the character described, the combination, with a base, of a pair of supporting devices carried thereby, rigid plates secured to the upper portions of said supporting devices, and lying adjacent to each other, said supporting devices comprising vertically yielding portions whereby said plates are supported in elevated position, means for maintaining substantially a fixed angular relation between said plates

- and said supporting devices, means for permitting a limited movement of said plates toward and from each other while maintaining said plates substantially horizontal at 5 all times, a plurality of leaves hingedly connected together at their inner edges, part of said leaves being supported upon each of said plates, and the point of connection of said leaves being between said plates.
- 10 3. In a device of the character described, the combination, with a base, of a pair of supporting devices separately pivoted thereto and capable of swinging toward and from each other, rigid plates secured to the upper 15 portions of said supporting devices, said supporting devices comprising flexible portions whereby said plates are supported yieldingly in elevated position, means for maintaining substantially a fixed angular 20 relation between said plates and said supporting devices, and a plurality of leaves hingedly connected together at their inner edges, part of said leaves being supported upon each of said plates and the point of 25 connection of said leaves being between said plates.
4. In a device of the character described, the combination, with a base, of lazy-tongs pivotally connected to separate longitudinal 30 portions thereof and capable of swinging toward and from each other, rigid plates secured to the upper ends of said lazy-tongs, and means yieldingly maintaining said lazy-tongs in extended position, the inner edges 35 of said plates lying adjacent to each other in separate vertical planes and the axes of said pivotal connections being substantially parallel to said planes, whereby each of said plates may receive the outermost of a series 40 of pivotally connected leaves and maintain the uppermost of said leaves in substantially a fixed plane, while permitting the transfer of leaves from one plate to the other.
5. In a device of the character described, 45 the combination, with a base, of a pair of lazy-tongs connected to opposite points of separate longitudinal portions thereof, means connecting together similar points of each pair of lazy-tongs whereby they are 50 caused to move together, a rigid plate secured to the upper ends of each pair of lazy-tongs, means yieldingly maintaining said lazytongs in extended position, the inner edges of said plates lying adjacent to each 55 other in separate vertical planes, whereby each of said plates may receive the outermost of a series of pivotally connected leaves and maintain the uppermost of said leaves in substantially a fixed plane, and means 60 permitting a limited movement of said plates toward and from each other whereby leaves may be transferred from one plate to the other.
6. The combination, with a base member, 65 of a pair of rigid supporting plates, exten-
- sible supporting means secured to the lower sides of said plates and making fixed angles with said plates, the lower ends of said supporting members being pivoted to said base member upon substantially parallel axes in 70 a manner that will permit of a slight movement toward and from each other, resilient means included in said supporting members whereby said plates are yieldingly held in elevated position, each of said plates being 75 adapted for the reception of the end leaf of a series of hinged leaves, the hinges of which fall between the adjacent edges of said plates.
7. The combination, with a base member, 80 of a pair of flat supporting plates, yieldingly supported independently of each other above adjacent portions of said base member, means maintaining said plates at substantially fixed angles relative to the horizontal plane, while permitting a restricted movement thereof toward and from each other, each of said plates being adapted for the reception of the end leaf of a series of hinged leaves, the hinges of which fall between the adjacent edges of said plates, and 85 means carried by said plates for fixing the position of said leaves thereon.
8. In a device of the character described, the combination, with a pair of rigid supporting plates having slotted ears at similar, transversely opposite portions thereof, of lazytongs having their free arms slidably engaged with said ears, a base member having brackets, the opposite ends of said lazytongs being pivotally connected on their longitudinal axes to said brackets, resilient members associated with said lazytongs whereby the latter are normally held in extended position, and a series of leaves, the outermost of which is applied to each of said plates, said leaves being hinged together in the space between the adjacent 90 edges of said plates.
9. In a device of the character described, 95 the combination, with a pair of rectangular, rigid, supporting plates, of supporting members secured to the lower surfaces of said plates substantially normal to the plane thereof, a base member, pivotal connections 100 between said base member and the lower end of each of said supporting members whereby said supporting members are permitted to swing toward and from each other, the axes of the pivots being substantially parallel 105 and spaced apart a distance not less than the width of one of said plates, each of said supporting members comprising yielding means tending to hold its plate in elevated 110 position, and a plurality of leaves hingedly connected together at their inner edges, part of said leaves being supported upon each of said plates, and the point of connection of 115 said leaves being between said plates.
10. In a device of the character described, 120

the combination, with a base member, of a pair of lazytongs pivoted to transversely opposite points of longitudinally spaced portions of said base member, rigid horizontal rods extending between similar points of intersection of each pair of lazytongs, a flat, rigid, supporting plate slidably connected to the upper ends of each pair of lazytongs, the width of each plate being less than the distance between the centers of said first pivots, expanding springs engaging said rods and normally maintaining said

plates in elevated position, and a plurality of leaves hinged together at their inner edges, part of said leaves being supported 15 on each of said plates and said hinges being received in the space between said plates.

In testimony whereof, I hereunto affix my signature in the presence of two witnesses:

GEORGE JACOBS.
